UNITED STATES PATENT OFFICE.

NATHANIEL B. WALES, OF BOSTON, MASSACHUSETTS, ASSIGNOR TO WALES STOKER COMPANY, OF HILLSDALE, MICHIGAN, A CORPORATION OF MICHIGAN.

APPARATUS FOR SMOKELESS COMBUSTION.

Application filed March 18, 1921. Serial No. 453,422.

To all whom it may concern:

Be it known that I, NATHANIEL B. WALES, a citizen of the United States, residing at Boston, in the county of Suffolk and State 5 of Massachusetts, have invented certain new and useful Improvements in Apparatus for Smokeless Combustion, of which the following is a specification.

This invention relates to a method of 10 promoting smokeless combustion in boiler furnaces and to apparatus for carrying it out.

The main purpose of this invention is to 15 provide for the introduction of air currents or jets into the fuel bed in such a manner that a portion will penetrate downwardly and cause the more volatile and bituminous products to burn within the confines of the fuel bed.

In the detailed description which follows, 20 I shall refer to the accompanying drawings in which—Figures 1, 2 and 3 are conventional sectional views, more or less diagrammatic, of a boiler fire-box illustrating the principles of combustion upon which my invention is based; Fig. 4 is a fragmentary 25 front elevation, partly in section, of a boiler, showing my invention applied to the fire boxes; Fig. 5 is a vertical sectional view taken on the line 5—5 of Fig. 4; and Fig. 6 is a similar vertical sectional view on the 30 line 6—6 of Fig. 4, except that the door is shown in the open position.

The air which supports combustion of the fuel on the grates of the fire boxes of furnaces, etc., is usually supplied from the ash pit below the grate and passes upwardly therethrough. This produces a rapid combustion of the fuel, resulting in an intense 35 heat, but the strong upward draft carries off large volumes of volatiles from the green coal and, if the temperature of the volatiles is below their ignition point, they are discharged into the stack as a dense cloud of smoke.

It has been heretofore proposed to overcome 40 this tendency to produce smoke and to induce a more intense burning at the surface of the fuel bed by introducing air under a forced draft, above the fuel bed. Under 45 certain conditions this is beneficial and results in a somewhat better combustion and consequently diminishes the amount of smoke to a certain extent, but it is far from satisfactory.

I have discovered that the smoke may be

practically eliminated by forcing air over the top of the fuel bed at such an angle as to produce a downward component sufficient to drive the volatiles and smoke downwardly partially through the bed of incandescent 60 fuel, thereby causing the ignition of said volatiles and combustible elements of the smoke within the fuel bed and driving the flames to the back of the bed as illustrated in Fig. 1 wherein the draft of air is directed 65 over the fuel bed at an angle of about 15°. If the angle of the entering draft is too great, the downward component will be sufficient to drive the flames downwardly into or through the grate bars, as illustrated 70 in Fig. 2, thereby endangering the integrity of the grate, causing it to warp and eventually destroying it. On the other hand, if the downward component is insufficient or entirely lacking, as when the forced 75 draft is directed upwardly, so that there is a corresponding upward component, as illustrated in Fig. 3, the evil will be increased since it is evident that the upward component tends to magnify the escape of volatiles and smoke from the fire bed. It will be evident therefore, that there is a critical 80 angle which is best suited for each particular condition, depending upon the depth of the fire bed and the distance above the bed 85 at which the forced draft is introduced. I have accordingly devised means for readily adjusting the height of the nozzle and the angle of inclination.

In the drawings, 10 represents the setting 90 of the usual commercial steam boiler, having fire boxes arranged in the ordinary manner with outwardly swinging fire doors 12, 12'. These doors are universally provided with rotatable shutters mounted in centrally disposed openings. I take advantage of this construction by removing the shutters and securing an attachment with an adjustable nozzle over the opening. The nozzle 14 may be in the form of an annular shell or casting 100 in which the opening is eccentrically located so that it may be adjusted in height by rotating the shell about its axis, while the outer periphery is rounded or arcuate in section so that the nozzle may be adjusted 105 to different angles by laterally shifting the position of the shell. The nozzle is carried by a plate 15 bolted or otherwise secured to the front plate of the fire-door and carries an integral upwardly extending tubular 110

member or hopper 17. The nozzle 14 may be secured in any adjusted position by means of a bolt or adjusting screw 18 which passes through the wall of the hopper 17 and presses or jams the nozzle member 14 against its arcuate seat in the plate 15. A blower or fan 20 driven by an electric motor 21 mounted on a suitable bracket 23, is connected to a stationary manifold 24 having 10 downwardly extending branches 25, 25' which connect with the ends of the hoppers 17 when the doors are in closed position, as illustrated in Fig. 5 and the left hand portion of Fig. 4. The lower ends of the manifold members 25, 25' are directed inwardly at such an angle that the blast of air will be directed into the fire-box when the door is open, as illustrated in Fig. 6 and the right hand portion of Fig. 4, thus constituting air 20 directing nozzles. This effect is enhanced by providing a short transverse partition 26 just within the open end of said manifold nozzle members.

The smoke period extends only for a limited time after the firing of fresh coal into the fire boxes and I therefore provide means for automatically starting the electric motor when either door is opened and for stopping the motor after 20 a predetermined length of time. For this purpose I have illustrated at 30 a conventional time switch having a projecting push-button or stem 31 which projects in the path of the door so that it will be 30 pushed inwardly when the door is swung open to thereby close the circuit of the motor and start the blower in operation. Any suitable time switch may be employed, such for instance as shown in U. S. Patents 40 921,761, May 18, 1909; 1,103,883, July 14, 1914; or 1,139,066, May 11, 1915. Accordingly, as soon as the door is opened the blower will cause a draft to blow through the nozzle opening 25 into the fire-box so 45 that a large volume of additional oxygen will be supplied along with the fresh fuel which is being thrown upon the grates and after the door is closed the blast of air will be directed through the manifold 50 24, nozzle opening 25 and through the nozzle 14 at just the proper angle to produce the necessary downward component to force the volatiles and smoke inwardly into the body of incandescent fuel and this will be 55 continued throughout the smoke period and at the end of this period the switch will automatically break the electric circuit to stop the operation of the blower.

From the above description it will be 60 observed that I have provided a method of producing practically smokeless combustion of coal and other solid fuels by supplying

the necessary additional quantity of oxygen throughout the stoking period and thereafter maintaining said additional supply of oxygen throughout the smoking period and directing the same upon the fuel bed at such an angle that a downward component thereof will carry the volatiles and smoke into the body of the incandescent fuel bed where 70 they will be consumed. I have also provided an apparatus which is adapted to carry out this method in commercial boilers by reason of the adjustability of the nozzle so that its distance above the fire bed may 75 be varied as well as its angle of inclination. I have described in detail the particular construction illustrated in the drawings for the purpose of clearly disclosing one embodiment of my invention but it will be evident to engineers that various changes and modifications may be made without departing therefrom.

I claim:

1. Apparatus for effecting smokeless combustion of a solid fuel in a combustion chamber provided with the usual fire door, comprising a motor-actuated blower, a manifold connected thereto and terminating in an air nozzle positioned above the fire door and directed inwardly toward the opening thereof, an air hopper fastened to said fire door and registering with said nozzle when the door is closed, said hopper protruding through said door and terminating in a second nozzle.

2. Apparatus for effecting smokeless combustion of a solid fuel, comprising a combustion chamber provided with a fire door, an air blower, and an air conduit or manifold connected to said blower and comprising separately supported inwardly directed nozzles, and means for causing said blower to discharge into the fire door opening through the nozzles in series when the door is closed and through one nozzle when the door is open.

3. Apparatus for effecting smokeless combustion in the fire-boxes of commercial boilers, comprising a hopper or conduit secured to the fire door and terminating at its lower end in a nozzle opening into the fire box above the grate, a blower, an electric motor connected thereto, a manifold connecting said blower to said hopper when the door is closed, a switch controlling said motor and adapted to break the circuit automatically after a predetermined period, and means actuated by the opening of the door for closing said switch.

In testimony whereof I affix my signature.

NATHANIEL B. WALES.
